UNITED STATES PATENT OFFICE.

JOHN N. AUER, OF PRAIRIE DU ROCHER, ILLINOIS.

COMBINED STEP-LADDER, BENCH, AND IRONING-BOARD.

1,245,082.

Specification of Letters Patent. Patented Oct. 30, 1917.

Application filed February 21, 1917. Serial No. 150,013.

To all whom it may concern:

Be it known that I, JOHN N. AUER, a citizen of the United States, residing at Prairie du Rocher, in the county of Randolph and State of Illinois, have invented certain new and useful Improvements in Combined Step-Ladders, Benches, and Ironing-Boards; and I do hereby declare the following to be a full, clear, and exact description of the invention, such as will enable others skilled in the art to which it appertains to make and use the same.

This invention relates to improvements in combined step ladders and ironing boards.

15 The object of this invention is the provision of an ironing board which may be converted into a step ladder or bench, or may be collapsed and placed away in a small place.

20 Another object of this invention is the provision of a combined ironing board, which may be easily and quickly applied to the edge of a support and positioned in operative position.

25 Another object of this invention is the provision of a combined ironing board, bench and ladder, which when in form of a bench, can be readily and quickly converted into a step ladder or ironing board, 30 and when it is in the form of an ironing board, one of the bench supports constitutes a clothes rack.

35 A further object of this invention is the provision of a device of this character, which shall be simple, practical and inexpensive to manufacture, and which may be sold at a comparatively low cost.

With these and other objects in view, the invention consists of the novel combination 40 and arrangement of parts hereinafter more fully described and set forth in the claims hereto appended.

In the drawings:

Figure 1 is a perspective view of the improved combined step ladder, bench and ironing board with the ironing board in operative position,

45 Fig. 2 is a perspective view illustrating the combined step ladder, bench and ironing board set up as a bench,

50 Fig. 3 is a perspective view of the device assembled and used as a ladder,

Fig. 4 is a detail view illustrating the manner in which the ironing board is journaled to the stiles of the ladder structure,

55 Fig. 5 is a side elevation illustrating the

combined step ladder, bench and ironing board in a collapsed position.

Referring more particularly to the drawings, the numeral 1 designates an ironing board which has one end tapered at its opposite side edges as at 2 to provide a supporting tread or base 3, the opposite end of the board 1 is reduced as at 4 and has secured on its lower side the shaft 5, adjacent the inner end thereof and the ends of this shaft project laterally beyond the opposite side edges thereof, as shown in Fig. 3.

The shaft 5 is rigidly secured to the under side of the board 1 by suitable rivets or the like as at 6 and has journaled to each end the stiles 7. The stiles 7 are held in spaced relation by the treads or steps 9, which are secured to the inner faces as at 10 at spaced distances apart. The stiles 7 have arranged on their inner faces adjacent their upper ends the bearing brackets 11, which receive the shaft 5 of the ironing board therein, thus pivotally securing the ironing board to the stiles 7 so that the same may be freely 80 swung between the upper ends thereof.

The upper ends of the stiles are provided on their outer sides adjacent the upper end thereof with the notches or cut out portions 12, the purpose of which will be hereinafter more fully described.

The lower ends of the stiles 7 are beveled as at 13 so as to constitute a support for coöoperating with the beveled end 3 of the ironing board 1 when the device is used as 90 a ladder structure.

A pair of brace rods 14, each have one of their ends journaled on the ends of the shaft 5 and are rigidly connected together by the horizontal brace bars 16, as shown in 95 all the figures of the drawings.

A second pair of braces 17 of the same length as the braces 14 are pivotally secured to the outer side of each stile 7 adjacent the lower end thereof as at 18 and each are 100 provided near their pivoted points with the openings 19. The braces 17 are rigidly connected together by the rods 20, which are arranged in superposed relation.

The braces 17 and 14 are used to support 105 the ladder stiles and ironing board 1 in a collapsed position, thus constituting a bench.

A supporting rod 21 has an enlarged end 22, which enlarged end is journaled on one of the reinforcing rods 20 carried by the 110 braces 17 as shown in Fig. 1. The reduced end of the support 21 is adapted to fit in

a socket 23 arranged on the under side of the board 1 near the beveled side edges 2 thereof, thus supporting the ironing board in a horizontal plane when in operative position. The stiles 7 are provided near their upper ends with horizontally aligned openings 24, which are adapted to receive a removable pin 25 therein when in a ladder position, thus limiting the movement of the 10 reduced end 4 of the ironing board 1 securing it between the upper ends of the stiles 7 and to prevent movement in the opposite direction, there is arranged in the notches 12 a removable pin 26, as clearly illustrated 15 in Fig. 3.

One of the braces 14 has arranged intermediate its end on one side edge, an eye 27, which is adapted to receive the hook 28 therein, which hook is pivotally secured to 20 one of the stiles 7 as at 29, when the device is in a collapsed position, as illustrated in Fig. 5.

The eye 30 is secured to the enlarged portion 22 of the support 21 and is adapted to 25 receive a hook 31 therein, which hook is carried by one of the treads 9.

When using the device as an ironing board, the reduced end 4 of the board is located under one edge of a support designated A in the drawings and this support 30 is clamped between the edge of the reduced portion 4 and the notches 12 of the stiles 7, the braces 14 are swung on their pivots on the shaft 5 up over the board 1 and are arranged in an inclined position and are held 35 therein by the removable pin 26 being located behind the braces 14 upon the upper side of the board 1, and the brace rods 16 may be used as a clothes rack when the device 40 is used as an ironing board. To support the free end of the ironing board, the brace rods 17 are turned upwardly on their pivot pins 18 and the support 21 has its end arranged in the socket 23 on the under side 45 of the board and these braces 17 are held against movement by removable pin 25 being arranged in the openings 19 in the brace rods 17, thus the device is used as an ironing board.

When it is desired to use the device as a 50 step ladder, the ironing board and stiles 7 are released from the support A, the pin 26 is removed from behind the braces 14 and the braces 14 are allowed to move in the 55 direction of the outer surface of the board 1, the removable pin 26 is then arranged between the outer surface of the board 1 and in the notches 12 of the stiles, thus holding the same against movement in one direction, 60 and the pin 25 is arranged in the openings 24, thus holding the board and stiles against movement in the other direction, the brace rods 17 and support 21 are moved out of engagement with the board 1 and swung upwardly as shown in Fig. 3 and connected 65

by the hook 31 and eye 30. The braces 14 constitute a support for a bucket of paint or the like when the device is used as a ladder and are held at right angles to the board and ladder by a removable bolt 33, which extends transversely through the reduced portion of the ironing board as shown in Fig. 3, thus supporting the arms 14 or braces 14 in a horizontal position.

When the device is to be used as a bench, 75 the pins 25 and 26 and bolt 33 are removed from their respective places, the board is allowed to rest upon the steps or treads 9 of the stiles, the pin 26 is then inserted back in the opening 24, thus preventing the outward movement of the braces 14 and the pin 25 is then inserted in the registering openings in the braces 17, thus bearing against the under side of one longitudinal edge of the stiles 7, thus holding the same 80 against further outward movement when the device is to be used as a bench.

When it is desired to collapse the device, all that is necessary is to remove the pins 25 and 26, swing the braces 14 and 17 on 90 their pivoted points 18 and 5 and position the braces 17 between the board 1 and stiles 7 and arrange the braces 14 over the board 1 and hook the same by the hook 28 and eye 25, thus the device is in a compact and 95 small bundle.

What is claimed is:

1. In a combined step ladder, ironing board and bench structure, a support comprising a pair of spaced stiles, treads connecting said stiles, notches in the inner edges adjacent one end of the stiles, an ironing board pivotally associated with the stiles adjacent the upper ends, said ironing board and stiles adapted to firmly clamp to the edges of the support for positioning the ironing board in a substantially horizontal position, braces arranged in pairs and pivotally secured to the stiles adjacent their lower ends, a support pivotally associated with the braces and engaging the board for holding the same in its horizontal position, and a second pair of braces pivotally secured to the stiles and ironing board adapted to be positioned at an incline above the upper surface of the ironing board to be used as a clothes rack, as and for the purpose specified.

2. In combination, a pair of spaced stiles, an ironing board, one end of the ironing board being reduced and provided on its under side with a shaft, said shaft journaled to the stiles adjacent the upper ends thereof, braces pivotally connected at one end to the shaft of the ironing board, rods connecting the braces together, a second pair of braces pivotally secured on opposite sides of the stiles adjacent the lower ends thereof and connected by rods, a support pivotally associated with the rods of the second named 130

braces, and removable pins associated with the stiles and braces and board to hold the same in various positions.

3. In combination a pair of spaced stiles, 5 an ironing board journaled to the stiles adjacent one end thereof, braces pivotally connected to the ironing board at one end thereof, rods connecting the braces together, a second pair of braces pivotally secured to 10 the stiles adjacent the free ends thereof, rods connecting said braces, a support piv-

totally associated with the rods of the second named braces, a removable pin associated with the stiles and braces and board to hold the same in various positions.

In testimony whereof I affix my signature in presence of two witnesses.

JOHN N. AUER.
